UNITED STATES PATENT OFFICE.

ANDREW D'ARINO AND MURRAY ALSOFRM, OF NEW YORK, N. Y.

DESIGN FOR A MIRROR.

Application filed September 12, 1925. Serial No. 14,771. Term of patent 7 years.

To all whom it may concern:

Be it known that ANDREW D'ARINO and MURRAY ALSOFRM, respectively, subjects of Italy and Austria, and residents of New York city, New York, have invented a new, original, and ornamental Design for Mirror, of which the following is a specification, reference being had to the accompanying drawing, forming part thereof, in which—

Fig. 1 is a front elevational view of a mirror embodying our new design; and

Fig. 2 is a cross-sectional view taken along line 2—2 in Fig. 1.

We claim:

The ornamental design for a mirror as shown.

Dated Jersey City September 10th, 1925.

ANDREW D'ARINO.
MURRAY ALSOFRM.
